G. W. JACQUES.

DUPLEX EYELETING MACHINE,
APPLICATION FILED JAN. 13, 1920.

1,425,016.

Patented Aug. 8, 1922

UNITED STATES PATENT OFFICE.

GEORGE W. JACQUES, OF STRATFORD, CONNECTICUT, ASSIGNOR TO THE SINGER MANUFACTURING COMPANY, OF ELIZABETH, NEW JERSEY, A CORPORATION OF NEW JERSEY.

DUPLEX EYELETING MACHINE.

1,425,016.

Specification of Letters Patent. Patented Aug. 8, 1922.

Application filed January 13, 1920. Serial No. 351,168.

To all whom it may concern:

Be it known that I, GEORGE W. JACQUES, a citizen of the United States, residing at Stratford, in the county of Fairfield and State of Connecticut, have invented certain new and useful Improvements in Duplex Eyeletting Machines, of which the following is a specification, reference being had therein to the accompanying drawings.

10 In fastener setting machines of the duplex type designed to set a pair of fasteners in mating pieces of material simultaneously, it has been proposed to employ a pair of telescopically arranged hollow punches and 15 sets cooperating with opposite ends of a central combined anvil and set allowing the punchings to be forced through the length of the punches where they may escape. In some cases the packing of the punchings has 20 caused a severe stress on the punches tending to burst them, and the punchings often escape from the punch ends at intervals in masses, causing discharges at the upper punch end, of sufficient violence near the operator's eyes to be annoying.

This invention has been more particularly designed to eliminate these objections, while at the same time securing other advantages applicable to machines of this type as well 30 as to other machines involving similar functions. To this end a hollow double-ended punch and set element has been substituted for the anvil and set in the machine above described, and solid end relatively movable 35 punch elements have been substituted for the hollow punches so that the punchings will be forced into the central double-ended punch element.

Means comprising a spring-pressed plunger 40 carried by the upper punch element is also provided for ejecting the punchings from the lower end of the double-ended punch and set and away from the operator on the retraction of the lower movable punch element.

Further objects and advantageous combinations and details of construction contemplated by this invention and applicable to fastener setting, punching or other machines 50 will appear from a more complete description of embodiments thereof disclosed in the accompanying drawings in which,—

Fig. 1 is a fragmentary view partly in section of a duplex eyeletting machine con-

structed according to this invention showing 55 the parts in one position in their cycle of operations;

Figs. 2 and 3 are fragmentary elevations partly in section showing the parts in other positions in their cycle; 60

Fig. 4 is a detail showing modified forms of punching elements; and

Fig. 5 is a cross section of one form of certain punching elements showing the punching ejector, the parts being in the position illustrated in Fig. 3. 65

A represents a portion of the feed frame of a duplex eyeletting machine such as is disclosed in the application of Eames & Jacques, Serial No. 199,498, filed Oct. 31, 1917, this 70 feed frame being in the form of a pivoted lever and having pivoted between lugs 1 and 2 integral therewith, a link 3 by which the lever A may be swung to cause the feed of the work being operated upon through the 75 machine. As shown in the above noted application feed motion is imparted to the lever A by a cam acting in time with the punching and setting instrumentalities to be described. At its outer end lever A is 80 provided with aligned bearings 4 and 4^a for the reception of sliding sleeves 5, 5^a, the adjacent ends of these sleeves having threaded therein hollow sets 6, 6^a slidably carrying 85 their non-adjacent ends as shown at 8 in enlarged heads.

Slidably mounted within sleeve 5 is a plunger 9 having a head 10 at its lower end arranged to contact with the head 8, the 90 sleeve 5 being counter-bored at 11 to provide an enlarged passage for sliding movement of the heads 8 and 10. A coil spring 12 surrounding the rod 9 and abutting at opposite ends against the end of the counter-bore 11 95 and head 10 serves to hold the plunger 9 at its downward limit of motion to project the punch element 7 to its extreme outward position relative to the set 6. The punch 7^a is similarly mounted within the sleeve 5^a. 100 Sleeves 5 and 5^a are normally held in retracted position by means of arms 13, 13^a engaging under enlarged heads 14, 14^a of sleeves 5 and 5^a, the levers 13, 13^a being urged outwardly by spring-pressed pins 15, 105 15^a. A support 16 fixed to the frame A carries a double-ended punch and set element 17 between the adjacent ends of sleeves 5, 5^a.

As shown in Fig. 5 element 17 is hollow, having a perforation 18 from end to end thereof, and is provided on each end with die faces 19, 19^a surrounding the perforation 18 and cooperating with the respective adjacent punch elements 7 and 7^a. Element 17 may be carried by the support 16 in the manner shown in the application above mentioned by means of fins on support 16 engaging opposite sides of a peripheral groove in the member 17. Mounted adjacent the punches 7 and 7^a and in position at suitable times to deliver eyelets thereto are the eyelet raceways 20, 20^a, which may be actuated in time with the punching and setting elements in the manner disclosed in the above mentioned application.

For imparting the punching and set movements to the respective elements, hammers 21 and 21^a similar to those shown in the above mentioned application, may be employed. As there disclosed, each hammer comprises a portion 22 adapted to contact at certain times with the end of the plunger 9 and spaced members 23, 24 arranged to contact with the enlarged head 14 of the sleeve member. These hammers are designed to be actuated by cams in the manner shown in the aforesaid application.

As shown also in Fig. 5, the upper punch member 7 is provided with a bore 25 counterbored at 26 to receive the head 27 of an ejecting plunger 28 slidable within the bore 25. A spring 29 bears at one end against the head 27 and at its other end against a threaded plug 30 adjustable in the upper end of the counterbore 26. The lower punch element 7^a is solid, and is provided with a reduced extremity to enter the die portion 19^a in member 17, a similar reduced extremity being formed on the punch 7 to cooperate with the die portion 19^a.

The operation of this mechanism is as follows: As shown, two pieces of material to be operated upon are inserted in the machine, one on either side of the member 17. On starting the machine, the hammers 21, 21^a swing toward each other, the feed element A at this time being positioned relative thereto so that the plungers 9, 9^a are engaged thereby, thus forcing the punch elements 7, 7^a toward the member 17. On a preliminary motion of the punch elements 7 and 7^a toward each other, the eyelet raceways 20, 20^a are in position to present eyelets to the punch elements which pass therethrough. The raceways are then caused to retract in a manner well known in the art, leaving one eyelet threaded on each punch element. When the punching ejector 28 strikes the surface of the upper piece of material, further motion of the member 21 in a direction to force punch element 7 downwardly, causes member 28 to be retracted against the pressure of spring 29.

Further motion of the punch elements 7, 7^a causes them to punch the two pieces of material against the die 17 forcing the punchings within the bore 18 thereof.

When the punches are engaged in the work, the feed cam then operates through link 3 to swing the frame A so that the plungers 9, 9^a are moved out of contact with their respective engaging faces of the hammers 21, 21^a so that they are now free to retract within the hammer heads between the set-actuating elements, such as are shown at 23 and 24. The spring 12, however, causes the punches to remain in contact with member 17. Hammers 21, 21^a are then further depressed to force the sleeves 5, 5^a toward each other whereupon the eyelets are forced through the holes punched in the material and are clenched between the sets 6 and 6^a and the clenching surfaces of member 17, the punch elements 7 and 7^a retracting meanwhile within the sets. The hammers 21, 21^a are thereupon retracted allowing the spring pins 15, 15^a to retract the sleeves 5, 5^a and with them the sets 6, 6^a. As soon as the punch heads, as shown at 8, are contacted by the ends of the sets the punch elements 7 and 7^a also begin to retract, the parts, however, being so timed that the punch element 7^a begins to retract somewhat before the punch element 7. As soon as the punch element 7^a is retracted sufficiently, the plunger 28 under compression of spring 29 forces the punchings downwardly and out of the remote or lower end of the bore 18. Immediately thereafter the punch element 7 is also retracted and the frame A is then swung to its original position for a repetition of the same cycle of operations.

In Fig. 4 is shown a modified and preferred construction of punch elements in which the central double-ended element 17' is provided instead of die portions with cutting edges 19', 19^a surrounding the central perforation 28', the cooperating punching elements in this case being anvil members, the upper one only being shown in this figure. This anvil member 7' is slightly larger in diameter than the mating cutting edge 19', and carries a punching ejector 28' mounted and operating in the same manner as the ejector 28. Anvil 7' is designed to be mounted telescopically within the set 6 in the same manner as punch element 7, and a similar anvil member, except that it is not provided with a punching ejector is designed to be substituted for the punch element 7^a, being telescopically mounted in the set 6^a. The cycle of operations for this mechanism is the same as aforesaid, except that the cutting is done by the central element 17' instead of by the cooperating punch and die elements, the punchings being forced into the bore 18'.

and thereafter ejected through the lower end of the member 17' by means of the ejector 28'.

The term "punching element" as used in this specification and claims is used to designate not only a punch having cutting edges but also the cooperating anvil or die member. It should be noted that the punchings are ejected after the feed and the setting of the fasteners and in a downward direction away from the operator where they can cause no annoyance.

Having thus described certain embodiments of this invention, though it is evident that it is not limited thereto but may be embodied in other forms and with many modifications, what is claimed is,—

1. In a machine of the class described, a hollow double-ended punch element, punch elements cooperating with opposite ends of said hollow element to punch a plurality of pieces of material and force the punchings into said hollow element, and means controlled by said cooperating punch elements for ejecting the punchings from said hollow element.

2. In a machine of the class described, a hollow double-ended punch element, punch elements movable toward and from opposite ends of said hollow element to punch a plurality of pieces of material and force the punchings within said hollow element, and means carried by one of said movable elements for ejecting the punchings from said hollow element.

3. In a machine of the class described, a hollow double-ended punch element, punch elements movable toward and from the opposite ends of said hollow element to punch two pieces of material and force the punchings within said hollow element, and means acting on the withdrawal of one of said movable elements to eject the punchings from one end of said hollow element.

4. In a machine of the class described, a hollow double-ended punch element, punch elements movable toward and from the opposite ends of said hollow element to punch two pieces of material and force the punchings within said hollow element, and means carried by one of said movable elements for ejecting the punchings from the remote end of said hollow element on withdrawal of the other movable element.

5. In a machine of the class described, a double, open-ended punch element, punch elements movable toward and from the opposite open ends of said double element to punch two pieces of material and force the punchings in opposite directions into said double element, and an ejector for forcing both punchings out from one end of said double element.

6. In a machine of the class described, an open double-ended punch element, punch

elements movable toward and from the open ends of said open element to punch two pieces of material and force the punchings within said open element, and a spring-pressed plunger carried by one of said movable elements in position to project within said open element to eject the punchings from said open element on the withdrawal of the other movable element.

7. In a fastener setting machine, an open double-ended combined punch and set element, a telescopically arranged punch element and set element movable toward and from each end of said open element and arranged at each cycle of operations to punch material and force the punchings into said open element and thereafter to set a fastening in the material punched, and means for ejecting the punchings made at both ends of said open element after the fastenings have been set.

8. In a fastener setting machine, a hollow double-ended combined punch and set, a telescopically arranged anvil and set cooperating with each end of said punch and set to punch material and force the punchings within the punch and to set a fastener in the material punched, and an ejector element carried by one of said anvils for forcing the punchings out of the remote end of said punch on the retraction of the other of said anvils.

9. In a fastener setting machine, a hollow double-ended combined cutting punch and set, a telescopically arranged anvil and set cooperating with each end of said combined punch and set, means acting to move said anvils against the ends of said combined punch and set to punch material placed therebetween and force the punchings into the hollow of said punch and set, then to press the telescopic sets toward said combined punch and set to set a fastener in each hole punched, then to retract said telescopic sets and then to retract said anvils, and a spring pressed ejector carried by one of said anvils and acting to force the punchings out from the remote end of said combined punch and set on the retraction of the other of said anvils.

10. In a machine of the class described, a feed frame, a hollow double-ended punch element carried thereby, punch elements carried by said feed frame and cooperating with opposite ends of said double-ended punch element to punch a plurality of pieces of material and force the punchings into said double-ended punch element, means to move said frame while the punch elements engage the work whereby to feed the work, and means for ejecting the punchings from said double-ended element.

11. In a machine of the class described, a hollow double-ended punch element, a pair of punch elements one cooperating with each

end of said double-ended element to punch two pieces of material therebetween and force the punchings into said double-ended element, means to move said elements while 5 in engagement with the work to feed the same, and means to eject the punchings from said double-ended element.

12. In a machine of the class described, a hollow punch element, a punch element co- 10 operating therewith to punch material and force the punching within said hollow element, means to move said elements while in contact with the work to feed the work, and means for ejecting the punching from 15 the hollow element.

13. In a machine of the class described, a hollow double-ended cutting punch, and an anvil cooperating with each end of said punch to force a plurality of pieces of material 20 against said punch to punch the same and force the punchings within said punch, and means carried by one of said anvils for 25 ejecting the punchings.

14. In a machine of the class described, a hollow double-ended cutting punch, an 25 anvil cooperating with each end of said punch to force a plurality of pieces of material against said punch to punch the same and force the punchings within said punch, 30 and means for ejecting both punchings from one end of said punch.

15. In a fastener setting machine, a hollow 35 double-ended combined cutting punch and set, a pair of anvils and sets telescopically arranged, one such anvil and set cooperat-

ing with each end of said hollow punch and set to punch two pieces of material and force the punchings within said hollow punch and set, and then to set fasteners in 40 said materials, and a spring-pressed element carried by one of said anvils and arranged to eject the punchings from said hollow punch and set on the retraction of the other of said anvils.

16. In a fastener setting machine, a feed 45 frame, a hollow double-ended punch and set element carried by said frame, a punch element and a set element telescopically arranged on said feed frame to cooperate with each end of said double-ended element, means 50 acting on the telescopic punch and set elements to punch a plurality of pieces of material and force the punchings within said double-ended element and then to set fasteners in the material, means acting to move 55 said frame to feed both pieces of work during engagement of said elements therewith, and means for ejecting the punchings from said double-ended element after the feed has taken place.

17. A machine of the class described comprising punching elements working each oppositely to the other and cooperating to punch a plurality of pieces of material substantially simultaneously, and means for 60 ejecting the punchings from said pieces of material downwardly.

In testimony whereof, I have signed my name to this specification.

GEORGE W. JACQUES.
